(57) **CLAIM**

The ornamental design for a outdoor fireplace with ash drawer, as shown and described.

DESCRIPTION

FIG. 1 is a perspective view showing our new outdoor fireplace with ash drawer;

FIG. 2 is a front elevational view thereof;

FIG. 3 is a rear elevational view thereof;

FIG. 4 is a right side elevational, the left side view thereof being a mirror image of that which is shown;

FIG. 5 is a top plan view thereof; and,

FIG. 6 is a bottom plan view thereof.
